UNITED STATES PATENT OFFICE.

VINTON E. SISSON, OF CHICAGO, ILLINOIS, ASSIGNOR TO UNION METAL PRODUCTS COMPANY, OF CHICAGO, ILLINOIS, A CORPORATION OF DELAWARE.

CORRUGATED WALL PLATE.

Application filed September 18, 1924. Serial No. 738,450.

The invention resides in forming corrugations or embossments in a metallic plate so as to increase its strength to resist exterior loads applied upon it. By forming said corrugations or embossments integral with the plate, considerable fabrication of other parts and riveting is eliminated, and furthermore, the ultimate weight of the structure is retained at a minimum.

Such integrally reinforced plates are especially adaptable for end walls of railway freight cars where the sifting of the lading causes severe impacts against the end wall. These integral reinforcements also resist the tendency to buckle, due to the torsional and weaving movements of the car in service. Such plate may also be used for the floor or roof of a railway car.

Such corrugations or embossments are mechanical beams and can be considered and calculated as such.

Car wall structures have been manufactured and are in extensive use wherein a series of straight parallel corrugations are formed in the plate which terminate within the edges thereof to form flat margins. Each corrugation is a beam and transmits any load imposed upon it to the side walls of the car and partially to the corrugation on either side of it.

Such structures are shown in my Patent No. 1,271,234, July 2, 1918; Reissue No. 14,434, February 19, 1918, and others; the Murphy-Sisson Patent No. 1,031,571, July 2, 1912 and other patents to Murphy. When the corrugations terminate within the edges of the plate, considerable pressure is required to form them as it is necessary not only to bend the metal but also to stretch and thin it; in fact, the plates are heated to a cherry red to make such deformation possible without tearing the metal. This heating is expensive and also handling cold plates is much faster than handling hot plates, which considerably affects the output of the plant. Higher grade steel plates must be used where stretching is required.

It has been proposed to extend the corrugations to the opposite edges of the sheet (see Murphy Patent No. 1,313,106, August 12, 1919), so that the corrugations may be bent or folded in the steel plate, without stretching or heating it. Corrugated angles and separate caps have been proposed to weather-proof that portion of the car adjacent the

termination of the corrugations, but such extra parts require careful and tight fitting, because if moisture were permitted to enter the car, it would ruin certain ladings.

It is considered impractical to extend the corrugation to the edge of the plate and then flange the corrugated plate, as the corrugations flatten out and the metal will frequently fracture; furthermore, the difficulty of waterproofing has not been eliminated.

The section modulus of a corrugation is determined by the amount of metal comprising it and the distance of such metal from the neutral axis of the corrugation, therefore, with the depth remaining constant and the thickness of material being the same, the wider the corrugation the greater the section modulus will be. (There are practical limitations to the width of a corrugation.)

An object of my invention is to corrugate a metal plate so as to obtain the strength value of a wide corrugation and also the manufacturing advantages of extending the corrugation to the edges of the plate and yet eliminate the disadvantages of stretching and heating the plate and the necessity of the extra weatherproofing parts.

In the drawings:

Fig. 1 is an end elevation of a railway box car with my invention applied thereon.

Fig. 2 is a section on line 2—2 of Fig. 1.

Fig. 3 is a fragmentary view in elevation of a termination of a corrugation.

Fig. 4 is a side elevation of Fig. 3.

Fig. 5 is a section on line 5—5 of Fig. 3.

Fig. 6 is a section on line 6—6 of Fig. 3.

Fig. 7 is a section on line 7—7 of Fig. 3.

Fig. 8 is a section of a corrugation having a constant height and perpendicular walls.

In the drawings the roof 1; end sill 2; striking casting 3; push pole pockets 4 and side walls 5, are all the usual parts of a railway box car. The metallic plates 6—7 are reinforced by corrugations 8 or 9 which extend substantially from side to side of the car and are secured to angle iron frame member 10 (corner post in illustrations) by rivets 11, which member is in turn secured to the car proper by flange 12. While the drawings show the corrugations positioned horizontally and the frame members positioned vertically, it is understood that these respective positions may be reversed and still come within the scope of my invention.

100

105

110

When a load is imposed upon a corrugation which extends to the opposite edges of the plate, the corrugation has a tendency to open up, i. e., for the two walls to separate. 5 This may be prevented by securing them together, for instance, as shown by rivets 16 or such action may be resisted by securing the plate to the adjacent frame member of the car (corner post if the corrugations 10 run horizontally or the end sill or end plate if the corrugations are positioned vertically) by means positioned on both sides of the corrugation and in close proximity thereto. It may be desirable to use both forms of preventative.

The corrugations extend to the opposite edges of the plate and comprise spaced apart walls 13—14 which converge until they are in contact (at 15) adjacent the edge of the 20 plate which provides a waterproof construction. The weatherproofing feature is further assured by positioning the walls at their ends in parallel relation for a short distance, as shown at 15, and preferably securing them together by rivet 16 or perhaps welding them.

The walls 13—14 are connected by tension members 17 and compression members 18 which are spaced in planes on either side 30 of the neutral axis 19—20. The wider these members are, the greater the section modulus of the beam, provided the tension member is approximately the same width as the compression member. The contour of the 35 corrugations may consist of a series of curves instead of straight lines as illustrated.

The length of the center line of the metal of any lateral cross section of the corrugated plate is the same, therefore, there is no 40 stretching of the metal in forming, but simply a bending process; for instance, the length of the center line of Fig. 6 is the same as the length of the center line of Fig. 7. It will be noted that the amount of 45 the plate shown on either side of the center line of the corrugation is the same in Figs. 6, 7 and 8. While the width (and perhaps the height) of the corrugations may vary, yet the length of the center line of the metal 50 of the corrugated portion of the plate normal to the corrugation is the same as before the corrugation was formed therein; in other words, the foreshortening of the overall dimension of the metallic plate, normal to the 55 corrugation, is substantially the same throughout the length of the corrugation. The greater height of the corrugation on line 6—6 is due to the walls being oblique 60 instead of perpendicular, the variation in height depending upon the variation in obliquity of the walls, the minimum height being at the ends of the corrugation where the walls are perpendicular. (See Fig. 5.) Corrugation 9 illustrates a form wherein the 65 side walls are of a constant obliquity and

constant width the major portion of their length, whereas corrugation 8 shows a construction wherein the walls are of varying obliquity and varying width. However, the walls 13—14 may be positioned perpendicular to the plane of the plate so that the height of the corrugation will remain constant, as shown by 21—22 in Fig. 8, in which case the length of the center line of Fig. 8 would be the same as the length of the center line of Fig. 7. 75

I claim:

1. A metallic plate having a varying depth corrugation formed therein extending to the opposite edges of the plate comprising spaced apart walls which converge to contacting relation adjacent the edges of the plate. 80

2. A metallic plate having a corrugation formed therein extending to the opposite edges of the plate comprising spaced apart walls which converge to contacting relation and are secured together adjacent the edges of the plate. 85

3. A metallic plate having a varying depth corrugation formed therein extending to the opposite edges of the plate comprising spaced apart walls which converge to contacting relation and are secured together adjacent the edges of the plate. 90

4. A metallic plate having a corrugation formed therein extending to the opposite edges of the plate comprising spaced apart walls which converge to contacting relation in parallel relation adjacent the edges of the plate. 100

5. A metallic plate having a varying depth corrugation formed therein extending to the opposite edges of the plate comprising spaced apart walls which converge to contacting relation in parallel relation adjacent the edges of the plate. 105

6. A metallic plate having a corrugation formed therein extending to the opposite edges of the plate comprising spaced apart walls which converge to contacting relation in parallel relation and are secured together adjacent the edges of the plate. 110

7. A metallic plate having a varying depth corrugation formed therein extending to the opposite edges of the plate comprising spaced apart walls which converge to contacting relation in parallel relation and are secured together adjacent the edges of the plate. 115

8. A metallic plate having a corrugation formed therein extending to the opposite edges of the plate comprising spaced apart walls which converge to parallel relation adjacent the edges of the plate. 120

9. A metallic plate having a varying depth corrugation formed therein extending to the opposite edges of the plate comprising spaced apart walls which converge to parallel relation adjacent the edges of the plate. 125

10. A metallic plate having a corrugation formed therein extending to the opposite edges of the plate comprising spaced apart walls which converge to parallel relation and are secured together adjacent the edges of the plate. 5
11. A metallic plate having a varying depth corrugation formed therein extending to the opposite edges of the plate comprising spaced apart walls which converge to parallel relation and are secured together adjacent the edges of the plate. 10
12. In a railway car, the combination of a metallic wall plate having a corrugation formed therein extending to the edge of the plate comprising spaced apart walls which converge to contacting relation adjacent the edge of the plate, and a frame member of the car adjacent the edge of said plate. 15
13. In a railway car, the combination of a metallic wall plate having a corrugation formed therein extending to the edge of the plate comprising spaced apart walls which converge to contacting relation in parallel relation adjacent the edge of the plate, and a frame member of the car adjacent the edge of said plate. 20
14. In a railway car, the combination of a metallic plate having a corrugation formed therein extending to the edge of the plate comprising spaced apart walls which converge to contacting relation in parallel relation and are secured together adjacent the edge of the plate, and a frame member of the car adjacent the edge of said plate. 25
15. A metallic plate having a corrugation formed therein extending to the opposite edges of the plate comprising spaced apart walls which converge to contacting relation in parallel relation adjacent the edges of the plate, whereby the foreshortening of the overall dimension of the metallic plate, normal to the corrugation, is substantially the same throughout the length of the corrugation. 30
16. A metallic plate having a varying depth corrugation formed therein extending to the opposite edges of the plate comprising spaced apart walls which converge to contacting relation in parallel relation adjacent the edges of the plate, whereby the foreshortening of the overall dimension of the metallic plate, normal to the corrugation, is substantially the same throughout the length of the corrugation. 35
17. A metallic plate having a corrugation formed therein extending to the opposite edges of the plate comprising spaced apart walls which converge to contacting relation adjacent the edges of the plate, whereby the foreshortening of the overall dimension of the metallic plate, normal to the corrugation, is substantially the same throughout the length of the corrugation. 40
18. A metallic plate having a varying depth corrugation formed therein extending to the opposite edges of the plate comprising spaced apart walls which converge to contacting relation adjacent the edges of the plate, whereby the foreshortening of the overall dimension of the metallic plate, normal to the corrugation, is substantially the same throughout the length of the corrugation. 45
19. In an end wall for a railway car, a metallic plate having a corrugation formed therein of varying width and varying depth which extends to the opposite edges of the plate. 50
20. A metallic plate having a corrugation formed therein extending to the opposite edges of the plate comprising spaced apart oblique walls which converge into contacting perpendicular walls and are secured together. 55
21. A metallic plate having a varying depth corrugation formed therein extending to the opposite edges of the plate comprising spaced apart oblique walls which converge into contacting perpendicular walls and are secured together. 60
22. A metallic plate having a corrugation formed therein extending to the opposite edges of the plate comprising spaced apart oblique walls which converge into contacting perpendicular walls and are secured together adjacent the edges of the plate. 65
23. A metallic plate having a varying depth corrugation formed therein extending to the opposite edges of the plate comprising spaced apart oblique walls which converge into contacting perpendicular walls and are secured together adjacent the edges of the plate. 70
24. A metallic plate having a corrugation formed therein extending to the opposite edges of the plate comprising spaced apart oblique walls which converge into contacting perpendicular walls in parallel relation and are secured together. 75
25. A metallic plate having a varying depth corrugation formed therein extending to the opposite edges of the plate comprising spaced apart oblique walls which converge into contacting perpendicular walls in parallel relation and are secured together. 80
26. A metallic plate having a corrugation formed therein extending to the opposite edges of the plate comprising spaced apart oblique walls which converge into contacting perpendicular walls in parallel relation and are secured together adjacent the edges of the plate. 85
27. A metallic plate having a varying depth corrugation formed therein extending to the opposite edges of the plate comprising spaced apart oblique walls which converge into contacting perpendicular walls in parallel relation and are secured together adjacent the edges of the plate. 90
28. A metallic plate having a corrugation formed therein extending to the opposite edges of the plate comprising spaced apart oblique walls which converge into contacting perpendicular walls in parallel relation and are secured together adjacent the edges of the plate. 95

- formed therein extending to the opposite edges of the plate comprising spaced apart oblique walls which converge into contacting perpendicular walls and are secured together 5 whereby the foreshortening of the overall dimension of the metallic plate, normal to the corrugation, is substantially the same throughout the length of the corrugation.
29. A metallic plate having a varying 10 depth corrugation formed therein extending to the opposite edges of the plate comprising spaced apart oblique walls which converge into contacting perpendicular walls and are secured together whereby the foreshortening 15 of the overall dimension of the metallic plate, normal to the corrugation, is substantially the same throughout the length of the corrugation.
30. A metallic plate having a corrugation 20 formed therein extending to the opposite edges of the plate comprising spaced apart oblique walls which converge into contacting perpendicular walls and are secured together adjacent the edges of the plate whereby the foreshortening of the overall dimension of 25 the metallic plate, normal to the corrugation, is substantially the same throughout the length of the corrugation.
31. A metallic plate having a varying 30 depth corrugation formed therein extending to the opposite edges of the plate comprising spaced apart oblique walls which converge into contacting perpendicular walls and are secured together adjacent the edges of the plate whereby the foreshortening of the overall dimension of the metallic plate, normal to the corrugation, is substantially the same throughout the length of the corrugation.
32. A metallic plate having a corrugation 35 formed therein extending to the opposite edges of the plate comprising spaced apart oblique walls which converge into contacting perpendicular walls in parallel relation and are secured together whereby the foreshortening of the overall dimension of the metallic plate, normal to the corrugation, is substantially the same throughout the length of the corrugation.
33. A metallic plate having a varying 40 depth corrugation formed therein extending to the opposite edges of the plate comprising spaced apart oblique walls which converge into contacting perpendicular walls in parallel relation and are secured together whereby the foreshortening of the overall dimension of the metallic plate, normal to the corrugation, is substantially the same throughout the length of the corrugation.
34. A metallic plate having a corrugation 45 formed therein extending to the opposite edges of the plate comprising spaced apart oblique walls which converge into contacting perpendicular walls in parallel relation and are secured together adjacent the edges of 50 the plate whereby the foreshortening of the overall dimension of the metallic plate, normal to the corrugation, is substantially the same throughout the length of the corrugation.
35. A metallic plate having a varying 55 depth corrugation formed therein extending to the opposite edges of the plate comprising spaced apart oblique walls which converge into contacting perpendicular walls in parallel relation and are secured together adjacent the edges of the plate whereby the foreshortening of the overall dimension of the metallic plate, normal to the corrugation, is substantially the same throughout the length of the corrugation. 70
36. In a railway car, the combination of a metallic wall plate having a corrugation formed therein extending to the edge of the plate comprising spaced apart walls which converge to contacting relation adjacent the edge of the plate, a frame member of the car adjacent the edge of said plate, and means to secure said frame member to said plate positioned on opposite sides of and close to 85 said corrugation.
37. In a railway car, the combination of a metallic wall plate having a corrugation formed therein extending to the edge of the plate comprising spaced apart walls which converge to contacting relation in parallel 90 relation adjacent the edge of the plate, a frame member of the car adjacent the edge of said plate, and means to secure said frame member to said plate positioned on opposite sides of and close to 95 said corrugation.
38. In a railway car, the combination of a metallic plate having a corrugation formed therein extending to the edge of the plate comprising spaced apart walls which converge to contacting relation in parallel 100 relation and are secured together adjacent the edge of the plate, a frame member of the car adjacent the edge of said plate, and means to secure said frame member to said plate positioned on opposite sides of and close to 105 said corrugation.
39. A metallic plate having a varying depth corrugation formed therein extending to the opposite edges of the plate comprising spaced apart oblique walls which converge into perpendicular walls in parallel 110 relation.
40. A metallic plate having a varying depth corrugation formed therein extending to the opposite edges of the plate comprising spaced apart oblique walls which converge into perpendicular walls in parallel 115 relation whereby the foreshortening of the overall dimension of the metallic plate, normal to the corrugation, is substantially the same throughout the length of the corrugation. 120
